UNITED STATES PATENT OFFICE.

JOHN EDWARDS, OF HARTWELL, NEAR LONGTON, COUNTY OF STAFFORD,
ENGLAND.

DESIGN FOR DINNER, TEA, AND TABLE WARE.

SPECIFICATION forming part of Design No. 15,598, dated December 9, 1884.

Application filed September 25, 1884. Term of patent 3½ years. Patented in England August 9, 1884, Nos. 10,957 and 10,958.

To all whom it may concern:

Be it known that I, JOHN EDWARDS, of Hartwell, near Longton, county of Stafford, England, have invented and produced a new and original Design for Dinner, Tea, and Table Ware, of which the following is a full, clear, and exact description.

Reference is to be had to the accompanying photographic illustrations, in which Figure 1 is a plan view of a dish-cover. Fig. 2 is a perspective view of a cover shown in place on a dish. Fig. 3 is a side elevation of a tea-pot, and Fig. 4 is a side elevation of a pitcher, these four views being deemed necessary to fully illustrate my design.

The leading features of my design consist of the representation of a fanciful head holding in its mouth the end of a fluted bar, and in the tapered beads with depressions at their sides upon the corners of the ware.

A represents a fanciful head holding in its mouth the end of a fluted bar, B.

When the design is used for the handle of a tea-pot, pitcher, or other similar ware, a single head A and bar B are used, as illustrated in Figs. 3 and 4.

When the design is used for the handle of a cover or dish, two heads A are represented as holding the opposite ends of the fluted bar B, as illustrated in Figs. 1, 2, and 3. Upon the four corners of the ware are tapered beads C, with depressions D along their sides, as shown in Figs. 1, 2, 3, and 4.

I claim—

1. In a design for table and toilet ware, a handle, the same consisting of a fanciful head holding in its mouth one end of a fluted bar that projects in front of the said head, as shown.

2. In a design for table and toilet ware, the representation of a cover having its corners provided with tapering beads C, and surmounted by two fanciful heads facing each other and joined by a fluted bar resting in their mouths, as shown.

JOHN EDWARDS.

Witnesses:

WILLIAM NIXON,
JOSEPH GOULDING.
